Primary Examiner — Anhdao Doan(74) *Attorney, Agent, or Firm* — Wolf, Greenfield & Sacks, P.C.(57) **CLAIM**

The ornamental design for a combined controller and cuff for remote ischemic conditioning, as shown and described.

DESCRIPTION

FIG. 1 is a top perspective view of the combined controller and cuff for remote ischemic conditioning;

FIG. 2 is a top, plan view thereof;

FIG. 3 is a bottom plan view thereof;

FIG. 4 is a front elevational view thereof;

FIG. 5 is a rear elevational view thereof;

FIG. 6 is a left side elevational view thereof; and,

FIG. 7 is a right side elevational view thereof.

The broken lines in the drawing views illustrate unclaimed portions of the combined controller and cuff for remote ischemic conditioning and form no part of the claimed design.
